H. C. AHRENS

SAUSAGE STUFFING APPARATUS

Filed July 19. 1922

Inventor

Herman C. Ahrens,

By C. W. Miley,
Attorney

UNITED STATES PATENT OFFICE.

HERMAN C. AHRENS, OF CINCINNATI, OHIO.

SAUSAGE-STUFFING APPARATUS.

Application filed July 19, 1922. Serial No. 576,103.

To all whom it may concern:

Be it known that I, HERMAN C. AHRENS, a citizen of the United States, residing at Cincinnati, in the county of Hamilton and 5 State of Ohio, have invented certain new and useful Improvements in Sausage-Stuffing Apparatus, of which the following is a specification.

My invention relates to improvements in 10 sausage stuffing apparatus. One of its objects is to provide improved means to render it impossible to move the plunger while the cylinder head is not clamped in operative position on the end of the cylinder, to avoid 15 injury to persons adjacent to the apparatus or waste of material. Another object is to provide means to render it impossible to actuate the fluid pressure valve to admit pressure below the plunger while the cylinder head is not in position upon the end of the cylinder. My invention also comprises 20 certain details and relation of component members, all of which will be fully set forth in the description of the accompanying drawings in which:

Fig. 1, is a plan view of a sausage stuffing apparatus embodying my invention with the cylinder head in place upon the cylinder.

Fig. 2, is a side elevation of the same.

Fig. 3, is a view similar to Fig. 1, with the cylinder head removed from the cylinder.

Fig. 4, is a side elevation of the upper portion of the cylinder taken at right angles to that shown in Fig. 2.

35 The accompanying drawings illustrate the preferred embodiment of my invention in which 15 represents the cylinder of a sausage stuffing apparatus having a plunger 16 movable upwardly therein due to the application of fluid pressure to the under face of the plunger. The plunger is preferably of considerable weight in order that when the fluid pressure below the plunger is released the weight of the plunger will be sufficient 40 to overcome the frictional resistance and the plunger will descend by gravity. At the upper end the cylinder is provided with one or more exit ports 17 to which nozzles 18 are fitted.

50 A yoke 19 is pivotally mounted upon a stud bolt 20 carried by an ear 21 projecting from the upper end of the cylinder. The yoke 19 is adjustable from a position across the upper end of the cylinder as shown in Fig. 1 to a position at one side of the upper end of the cylinder as shown in Fig. 2. The

movement of the yoke 19 is limited at one end by the engagement of a bolt 22 carried at the free end of yoke 19 with a recess 23 in an ear 24 projecting from the upper end 60 of the cylinder, and at the opposite end of its movement the yoke 19 is limited by the engagement of a portion of flange 25 carried by the yoke 19 with the side of the cylinder as shown in Fig. 3. The bolt 22 also 65 serves to clamp the free end of the yoke 19 firmly to the upper end of the cylinder.

A cylinder head 26 is pivotally mounted upon the lower end of a press screw 27, which screw is threaded through the central 70 portion of the yoke 19. A hand wheel or hand lever 28 rigidly mounted upon the upper end of the press screw 27 provides for adjusting the cylinder head to and from the upper end of the cylinder, and for holding or locking the cylinder head firmly in place upon the end of the cylinder. A ground metal joint at 29 is preferably provided between the cylinder head and the upper end of the cylinder. The lower end 75 of the cylinder may be closed in any desired manner, as for instance by means of a head 30 bolted to the lower end of the cylinder.

Fluid pressure, preferably air under pressure is applied through the conduit 31 to the lower end of the cylinder below the plunger 16 to force the plunger 16 upwardly in the cylinder. Without suitable provisions to safeguard the operation, an operator or unauthorized person is liable to apply air 80 pressure to the under face of the plunger while the cylinder head is not properly secured and locked in place upon the upper end of the cylinder, thereby forcing the heavy plunger out of the cylinder at the 85 upper end thereof to cause property damage and personal injury.

In order to safeguard the operation of the apparatus I provide for taking the supply of compressed air from a storage reservoir or direct from a compressor through a conduit 33 to a three-way controlling cock or valve 34 controllable by means of a hand lever 35 to direct a supply of air under pressure from the conduit 33 to the lower end 100 of the cylinder through the conduit 31, or to exhaust the air from the lower end of the cylinder through the conduit 31 and an exhaust conduit 36.

In order that the hand lever 35 may not be actuated to supply air under pressure to the cylinder through the conduit 31 except when 105

the cylinder head 26 and yoke 19 are properly positioned above the upper end of the cylinder, I provide a bolt or plunger 38 which is actuated from the hand lever 35 by means 5 of a connecting link 39, and is guided to move vertically in and by a vertical recess 40 in the projection 21. The flange 25 which rides over the upper face of the projection 21 is also provided with a vertical recess 41 10 which registers with the recess 40 when the yoke 19 and cylinder head are in position above the cylinder to permit the upper end of plunger 38 to move upwardly from the recess 40 into the recess 41, and thereby 15 permits the hand lever 35 to be moved to a position to supply air under pressure to the lower end of the cylinder, but prevents the cylinder head being moved from above the upper end of the cylinder until the hand 20 lever 35 has been adjusted to cut off and exhaust the air supply, and also prevents the hand lever being employed to admit air under pressure to the cylinder until after the cylinder head and yoke have been 25 adjusted to position over the end of the cylinder with the recess 41 registering with the recess 40.

A careless operator is also liable to operate the hand wheel 28 to break the joint 29 30 between the cylinder head 26 and the upper end of the cylinder while there is an air pressure acting upon the plunger to force the plunger upwardly, thereby forcing the charge of meat in the cylinder above the 35 plunger out between the cylinder head and upper end of the cylinder, to thereby cause property damage or injury. In order to provide against such injury or damage I 40 provide a spring actuated air valve 43 preferably attached concentrically with the yoke 19 to the upper end of the bolt 20 by means of which the yoke 19 is pivoted to the projection 21. The valve 43 is connected by a branch air conduit 44 with the air conduit 31. The valve 43 is normally held closed by means of a spring located therein, and said valve is provided with a stem or 45 projection 45 which is in position to be engaged by one end of a lever 46, which is pivotedly mounted in the forked end of a bracket 47 attached to the yoke 19. The opposite end of bracket 47 is forked and spans the upper end of the press screw 27 between the hand wheel 28 and a collar 48 adjustably 50 attached to the press screw by a set screw. When the press screw is employed to force the cylinder 26 head upon the end of the cylinder, the end of lever 46 is released from 55 engagement with the valve stem 45, and the 60 valve 43 is closed allowing air under pressure to accumulate in the cylinder below the plunger. As soon as the hand wheel 28 is actuated to break the joint 29 between the cylinder and cylinder head, the collar 48 65 is elevated thereby actuating the lever 46

causing its end to engage the valve stem 45 70 to open the valve 43 and exhaust the air under pressure from the lower portion of the cylinder, thereby automatically providing against damage or injury.

In operation a quantity of sausage meat is charged into the open upper end of the cylinder, the cylinder head is adjusted to position and closed upon the upper end of the cylinder and air under pressure admitted 75 to the lower end of the cylinder below the plunger, which causes the plunger to rise and force the meat out through the nozzles 80 18 over which sausage casings have been previously drawn.

The apparatus herein shown and described is capable of considerable modification within the scope of the claims without departing from the spirit of my invention.

What I claim is:

1. Sausage stuffing apparatus comprising a cylinder a plunger mounted therein, a yoke pivotally attached to said cylinder a press screw carried by said yoke, a cylinder head mounted upon said press screw and adapted to be applied to and removed from one end of said cylinder, a fluid conduit leading to said cylinder and through which fluid pressure is adapted to be applied to one end of said plunger, a controller valve operable to apply fluid pressure to and exhaust fluid under pressure from said cylinder, and means operable in unison with the movements of said controller valve and operable only when said yoke is in position for the cylinder head to close the cylinder to safeguard the operation of said controller valve.

2. Sausage stuffing apparatus comprising a cylinder a plunger mounted therein, a yoke pivotally attached to said cylinder, a press screw carried by said yoke, a cylinder head mounted upon said press screw and adapted to be applied to and removed from one end of said cylinder, a fluid conduit leading to said cylinder and through which fluid pressure is adapted to be applied to one end of said plunger, a controller valve operable to apply fluid pressure to and exhaust fluid under pressure from said cylinder, means to manually shift said controller valve from 105 exhaust to supply position, a bolt operable in unison with the movements of said valve shifting means, and a member carried by said yoke and interposed in the path of said bolt except when said yoke is in position 110 for the cylinder head to close the cylinder, to prevent shifting said controller valve to supply position except when said yoke is in 115 a predetermined position.

3. Sausage stuffing apparatus comprising 125 a cylinder, a plunger mounted therein, a yoke pivotally attached to said cylinder a press screw carried by said yoke, a cylinder head mounted upon said press screw and adapted to be applied to and removed from 130

one end of said cylinder, a fluid conduit leading to said cylinder and through which fluid pressure is adapted to be applied to one end of said plunger, a controller valve 5 operable to supply fluid pressure to and exhaust fluid under pressure from said cylinder, an automatically closed supplemental exhaust valve mounted concentrically with said yoke and connected by means of a 10 branch fluid conduit with said main fluid conduit, and means actuated in unison with the movements of said press screw to open said supplemental exhaust valve whenever said press screw is actuated to loosen said 15 cylinder head from the cylinder.

4. Sausage stuffing apparatus comprising a cylinder a plunger mounted therein, a yoke pivotally attached to said cylinder, a press screw carried by said yoke, a cylinder 20 head mounted upon said press screw and adapted to be applied to and removed from one end of said cylinder, a fluid conduit leading to said cylinder and through which fluid pressure is adapted to be applied to 25 one end of said plunger, a controller valve operable to apply fluid pressure to and exhaust fluid under pressure from said cylinder, means to manually shift said controller valve from exhaust to supply position, a bolt operable in unison with the movements 30 of said valve shifting means, and a member carried by said yoke and interposed in the path of said bolt except when said yoke is in position for the cylinder head to close 35 the cylinder, to prevent shifting said controller valve to supply position except when said yoke is in a predetermined position, an automatically closed supplemental exhaust valve mounted concentrically with 40 said yoke and connected by means of a branch fluid conduit with said main fluid conduit, and means actuated in unison with the movements of said press screw to open said supplemental exhaust valve whenever

said press screw is actuated to loosen said 45 cylinder head from the cylinder.

5. Sausage stuffing apparatus comprising a cylinder a plunger mounted therein, a yoke pivotally attached to said cylinder a press screw carried by said yoke, a cylinder head 50 mounted upon said press screw and adapted to be applied to and removed from one end of said cylinder, a fluid conduit leading to said cylinder and through which fluid pressure is adapted to be applied to one end of 55 said plunger, a controller valve operable to apply fluid pressure to and exhaust fluid under pressure from said cylinder, an automatically closed supplemental exhaust valve mounted concentrically with said yoke and 60 connected by means of a branch fluid conduit with said main fluid conduit, a lever pivotally mounted upon said yoke and having one end operatively connected with said press screw and its other end in position to 65 engage the stem of said supplemental exhaust valve to open said supplemental exhaust valve and exhaust the pressure in the cylinder whenever said press screw is actuated to loosen the cylinder head from the 70 end of the cylinder.

6. Sausage stuffing apparatus comprising a cylinder, a plunger mounted therein, a yoke pivotally attached to said cylinder, a cylinder head means to apply said cylinder 75 head to the end of said cylinder and release it therefrom, means to apply fluid pressure to one end of said plunger, an exhaust valve connected with the pressure end of said cylinder by a fluid conduit, and means 80 actuated in unison with the movements of said cylinder head to open said exhaust valve and exhaust pressure from said cylinder whenever said cylinder head is loosened from the end of said cylinder. 85

In testimony whereof I have affixed my signature.

HERMAN C. AHRENS.
